UNITED STATES PATENT OFFICE

GLENN W. MERRITT, OF BOWERSTON, OHIO, ASSIGNOR TO MINING SAFETY DEVICE COMPANY, OF BOWERSTON, OHIO

ROTARY CAR DUMP

Application filed December 15, 1928. Serial No. 326,228.

This invention relates to a rotary dump mainly designed for dumping mine cars, the general object of the invention being to provide a supporting structure provided with a rim at each end thereof, and two pairs of wheels which are engaged by the rims, one pair of wheels arranged at one side of the apparatus being connected to a drive shaft with means for holding the rims out of engagement with the drive wheels when the structure is in normal or unloading position and means associated with one of the drive wheels for giving the structure an initial movement whereby its rims will engage the drive wheels and the structure will be given a complete revolution.

Another object of the invention is to provide stop means for holding the structure in its normal or non-dumping position with its rims out of engagement with the drive wheels, with single means for moving the stop means to releasing position and giving the structure its initial movement.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein the characters denote like or corresponding parts throughout the several views, and in which:

In the drawings:

Figure 1 is an elevation of the apparatus.

Figure 2 is an end view showing the structure in its normal or non-dumping position.

Figure 3 is a similar view but showing the stop means in releasing position and the structure ready to be given its initial movement.

Figure 4 is an end view showing the parts with the structure in dumping position.

Figure 5 is a similar view showing the structure just before it completes its rotary movement.

Figure 6 is an enlarged sectional view showing the clutch assembly and the front end of the drive shaft.

In these views 1 indicates the frame or

structure for supporting the mine car A, this structure having the rims 2 at its ends. A pair of shafts 3 and 4 are supported on a base 5 and the shaft 3 has a pair of flanged wheels 6 loosely mounted thereon while the shaft 4 has a pair of plain wheels 7 and 7' fastened thereto. This shaft 4 also carries a pair of larger wheels 8 and 8' which are loosely mounted on the shaft and each larger wheel is placed adjacent the outer face of the plain wheel. The rims 2 rest upon the wheels 6 and the wheels 7 and 7' but when the structure or frame 1 is in normal or non-dumping position recesses 9 formed in the rims 2 will be opposite the wheels 7 and 7' with shoes 10 passing through the rims adjacent the recesses engaging the larger wheels 8 and 8', so that the rims will not be in engagement with the wheels 7 and 7'. Thus the shaft 4 with the wheels 7 and 7' can be constantly driven without imparting their movement to the structure 1.

A spring stop 11 arranged on a shaft 12 supported by the brackets 13 from the base 5, engages the shoe 10 which is in engagement with the wheel 8 and acts to hold the structure in normal or non-dumping position.

The wheel 8 has a plurality of pins 14 passing through the same, a grooved collar 15 being fastened to the outer ends of these pins and a clutch part 16 being fixed to the inner end. This clutch part is adapted to engage a clutch face 17 on the wheel 7 when the clutch part is moved towards the wheel 7, thereby connecting said wheel 8 with the wheel 7 so that said wheel 8 will rotate with the wheel 7 and the shaft. As the said wheel 8 is in engagement with one of the shoes 10 this movement of the wheel 8 will be imparted to the frame 1, through means of said shoe 10 so that the frame is given its initial movement. This initial movement of the structure will cause the recessed portions of the rims to move away from the wheels 7 and 7' so that the rims will engage these wheels and as these wheels are attached to the constantly driven shaft the rims and the frame 1 will be given a rotary movement so that the car will be dumped and returned to upright position.

A lever 18 is connected by the link 19 with the clutch fork 20 and by the link 21 with the arm 22 on the shaft 12, so that when the lever is manipulated the clutch will be moved into engagement with the wheel 7 and at the same time the shaft 12 will be rocked to move the stop 11 out of the path of the shoe 10, thus moving the stop to operative position and giving the structure its initial movement at the same time. After the rims are in engagement with the wheels 7 and 7' the lever is moved back to its normal position so as to place the stop in position to engage the shoe 10 after the structure has made a complete revolution and to release the wheel 8 from the wheel 7.

It will be, of course, understood that the frame 1 is provided with a track 23 which is in alignment with the track 24 when the frame 20 is in normal or non-dumping position so that a car can pass from the track 24 upon the track 23. Flanges 25 are arranged on the frame and on the car to hold the car in place during the dumping operation and a deflector plate 26 is arranged adjacent one side of the frame for deflecting the material from the car to a point under the device.

In order to prevent the wheel 8 from slipping on the shoe when the wheel is given its initial movement I provide the shoe with a pointed projection 27 which is engaged by pins 28 on the wheel so that as a pin strikes a projection it will cause the shoe and, therefore, the rim, to move with the wheel. The pins are slightly pointed as shown so that there is no danger of the projection riding on the pin if the two should strike each other as they come together. If this should occur the pointed part of the projection striking the pointed part of the pin would cause the parts to slip off of each other, this being permitted due to the fact that the wheel 8 is free to move.

From the foregoing it will be seen that I have provided means whereby the drive shaft can be constantly rotated such as by a motor M without imparting its movement to the car supporting structure but as soon as the clutch is thrown into action and the stop 50 moved out into inoperative position the structure is given its initial movement which will place its rims in engagement with the wheels fastened to the drive shaft and thus the movement of the drive shaft will be imparted to the structure.

It is thought from the foregoing description that the advantages and novel features of my invention will be readily apparent.

I desire it to be understood that I may 60 make changes in the construction and in the combination and arrangement of the several parts, provided that such changes fall within the scope of the appended claims.

Having described the invention, I claim:

1. An apparatus of the class described

comprising a car supporting structure having rims at its ends, a pair of shafts arranged under the structure, one on each side of the center thereof, a pair of wheels loosely arranged on one shaft and with which the rims engage, means for driving the other shaft, a pair of wheels fastened to this shaft and engaging the rims, each rim having a recess therein, a shoe fastened to each rim adjacent the recess, a pair of idler wheels on the drive shaft and engaging the shoes for holding the rims out of engagement with the wheels fastened to the drive shaft, clutch means for connecting one of the idler wheels with one of the fast wheels whereby the engagement 70 of the idler wheels with the shoe will give the structure an initial movement to cause its rims to engage the fast wheels, stop means for engaging one of the shoes to hold the structure with the recesses in the rims over 80 the drive wheels and means operated by the clutch actuated means for moving the stop means to inoperative position.

2. An apparatus of the class described comprising a car supporting structure having rims at its ends, a pair of shafts arranged under the structure, one on each side of the center thereof, a pair of wheels loosely arranged on one shaft and with which the rims engage, means for driving the other shaft, a pair of wheels fastened to this shaft and engaging the rims, each rim having a recess therein, a shoe fastened to each rim adjacent the recess, a pair of idler wheels on the drive shaft and engaging the shoes for holding the rims out of engagement with the wheels fastened to the drive shaft, clutch means for connecting one of the idler wheels with one of the fast wheels whereby the engagement of the idler wheels with the shoe will give the structure an initial movement to cause its rims to engage the fast wheels, stop means for engaging one of the shoes to hold the structure with the recesses in the rims over the drive wheels and means operated by the clutch 90 actuated means for moving the stop means to inoperative position, said shoe having a pointed projection thereon and pins carried by the clutch carrying idler wheels for engaging said projections.

In testimony whereof I affix my signature.

GLENN W. MERRITT.
